UNITED STATES PATENT OFFICE.

HOMER J. HOYT, OF DETROIT, MICHIGAN, ASSIGNEE TO MORGAN & WRIGHT, A CORPORATION OF MICHIGAN.

OPERATING DEVICE FOR MIXING-MACHINES.

1,317,298.

Specification of Letters Patent. Patented Sept. 30, 1919.

Application filed February 10, 1915. Serial No. 7,253.

To all whom it may concern:

Be it known that I, HOMER J. HOYT, a citizen of the United States, residing in Detroit, county of Wayne, State of Michigan, have invented certain new and useful Improvements in Operating Devices for Mixing-Machines, of which the following is a full, clear, and exact description.

This invention relates to machines for mixing liquid or plastic materials, and particularly such materials as are compounded with volatile ingredients, such as gasolene or alcohol. The machine is particularly applicable to use in mixing tire cement or rubber cement for other purpose or use.

Generally speaking, the machine consists of a closed chamber or tank within which is revolvably mounted a series of blades or paddles which act as beaters and cause the cement to flow in certain currents so as to present all of the materials to the action of the paddles or beaters.

This invention also comprises certain features of improvement in construction and arrangements of parts which will be hereinafter more fully pointed out and claimed in the accompanying claims.

For a detailed description of one form of this invention, reference may be had to the following specification and the accompanying drawing, which is a vertical sectional view taken through the central shaft of the machine.

The numeral 1 indicates a cylindrical casing forming a tank or chamber to contain the material to be treated. The top of the casing 1 is closed by a horizontal cover or head 2 which is secured in position on the casing 1 by means of a series of bolts 3. A gland or packing 4 is preferably inserted between the top of the casing 1 and the cover or head 2. The plate 2 is preferably formed in the shape illustrated as a casting and has integrally connected with it a bearing 5 for a horizontal driving shaft 6. A chamber formed by the vertical wall 9 is adapted to contain the beveled driving gears 10 and 11, the gear 10 being mounted upon the inner end of the horizontal shaft 6 and the gear 11 being mounted on the vertical driving shaft 13 which operates the beaters or paddles within the casing 1. The wall 9 of the chamber just referred to is provided with a bearing 12 for the upper end of the

shaft 13 on which is mounted the blades 55 or paddles 14, 15 and 16. A plate 17 having a liquid-tight bearing 18 closes the lower side of the chamber just referred to, while the top thereof and the top of the bearing 12 are closed by a plate 19 which is bolted 60 to the walls of said chamber. Upon removal of the plate 17 the gears 10 and 11 may be removed through the bottom of the casing, and upon removal of the plate 19 access may be had to the interior of both the 65 casing and the bearing 5. The plate 19 carries a horizontal and downwardly projecting arm 20 by means of which the cover 2 may be applied or removed, the arm having a bearing 21 at its outer end for supporting 70 the end of the shaft 6 and also providing a space for the accommodation of the loose and the keyed pulleys 22 and 23. The gear chamber is provided with a suitable plug 24 for the insertion of oil or other lubricant for 75 lubricating the gears. One or more hand-holes are provided, one of said holes being shown in dotted lines and indicated by the reference 26, through which the cement or other materials may be introduced prior to 80 treatment. The hubs of the beaters 14, 15 and 16 are keyed to the central shaft 13 and are also provided with set screws to firmly hold them in position. The central hub 28 is provided with a series of adjustable screws 29 to permit an accurate placing of the beaters on the shaft 13. The lower edges of the inclined blades 14 and 15 are provided with hard steel plates 30 to prevent 85 wearing and to allow renewal of the edges 90 when necessary. Upon the inner surface of the casing 1 are a plurality of concentric rings 31 carrying projecting brackets 32, upon the upper edges of which are fixed steel or similar wearing plates 33. The plates 33 95 are located just below the plane of the lower surfaces of the plates 30 of the beaters 14 and 15. It will be noted that all of the beaters or blades are inclined in the same direction and also rotate in the same direction, 100 thereby tending to force the material in contact with them along the same path and establishing a definite current.

The bottom of the casing is provided with a socket 34 within which is a series of steel 105 washers or annular plates 35 which form a thrust bearing for the lower end of the shaft 13. The socket 34 is provided with a screw-

threaded plug 36, by the removal of which the lubricant may be drawn off and any foreign matter removed.

The upper end of the casing communicates with an inlet pipe not shown by which air pressure may be supplied above the cement or similar material within the casing 1, and the bottom of the casing is provided with an outlet 38 through which the material may be forced by the air pressure above the same when it is not sufficiently liquid to run off under the force of gravity alone.

By the arrangement of parts above set forth, it will be noted that a very efficient and compact apparatus is provided in which the driving mechanism is completely protected from contact with the material being treated. At the same time all of the parts are easily accessible for inspection and adjustment, while the closed casing for the gearing permits the gearing to be lubricated by large quantities of oil or other lubricant without danger of having the lubricant becoming mixed with the material being treated within the casing. The fact that the main driving shaft is supported entirely by the casing itself, affords a unitary structure and obviates the necessity of using shaft hangers or other supports in connection with the machine. The auxiliary casing being closed by the plate on which is mounted the bracket for the driving shaft, causes the said plate to perform a double function which increases the compactness and stability of the parts. The providing of hand-holes in the cover of the casing obviates the necessity of removing the entire top for the insertion of the material to be treated.

The said inlet pipe, not shown, may also be employed for supplying air under pressure when the nature of the contents of the mixer requires the same, and, if necessary, the pipe may be connected with a source of vacuum or partial vacuum or with a suitable condenser for condensing or recovering the volatile components of the material being treated.

I do not wish to be understood as being limited to the exact details of form or arrangement of parts herein set forth, for

various changes may be made without departing from the essentials of the invention.

What I claim and desire to protect by Letters Patent is:

1. The combination with a cover for a mixing machine, of a casing integral therewith, a vertical bearing integral with the casing, a shaft journaled at the upper end in the bearing, a removable plate closing the bottom of the casing, a liquid-tight bearing for the shaft integral with the plate, a horizontal bearing in the wall of the casing, a shaft journaled in the horizontal bearing, and gears in the casing connecting the shafts, the gears being removable through the bottom of the casing upon removal of the plate.

2. In combination, a cover for a mixing machine and a casing integral therewith, a vertical bearing integral with the casing, a shaft journaled at the upper end in the bearing, a curved arm operatively connected with the cover and by means of which the cover may be applied and removed from the mixing machine, a horizontal bearing in the arm, a horizontal bearing in the wall of the casing, a shaft journaled in the horizontal bearings, driving means on the last named shaft embraced by the curved arm, and gears inside the casing connecting both of the shafts.

3. The combination with a cover for a rubber cement mixing mill, of a casing carried thereby, said casing being provided with an opening for the removal of gears, a plate for closing said opening, a vertical bearing carried by said casing, a vertical shaft journaled in said bearing, a liquid tight bushing for said shaft secured to said casing, a horizontal bearing supported by the casing, a shaft journaled in the horizontal bearing and gears in the casing connecting the shafts.

Signed at Detroit, county of Wayne, State of Michigan, this 20th day of January, 1915.

HOMER J. HOYT.
